TRACTOR

Theodore H. Koeber, Barrington, George E. Bowman,
Country Club Hills, and Mitchell Edward Kolak, Palatine, Ill., assignors to International Harvester Company, Chicago, Ill., a corporation of Delaware

Filed Mar. 23, 1967, Ser. No. 6,364

Term of patent 3½ years

(Cl. D14—3)

FIG. 1.

FIG. 2.

Fig. 3.

Fig. 4.

FIG. 5.

FIG. 6.

We claim:

The ornamental design of a tractor, substantially as shown and described.
